UNITED STATES PATENT OFFICE

2,643,037

COAT HANGER

Grace M. Clover, San Jose, Calif.

Application July 29, 1949, Serial No. 107,479

1 Claim. (Cl. 223—91)

1

The present invention relates to coat hangers and is concerned more particularly with an improved coat hanger construction which provides a plurality of means for carrying various types of garments, which lends itself by virtue of its construction to plastic molding operations, and which is formed to provide a strong hanger of long life and economical construction.

The above and other objects of the invention will be apparent from the following description of a preferred embodiment thereof, as illustrated in the accompanying drawings, in which:

Figure 1 is a perspective view of a coat hanger embodying the invention.

Figure 2 is a transverse sectional view through the coat hanger taken as indicated by the line 2—2 in Figure 1.

Figure 3 is a view similar to Figure 2 but showing the coat hanger in open position.

Referring to the drawings, the coat hanger comprises a pair of opposed hanger elements 10 and 11 which have a hinged connection by means of respective hinge elements or arms 12 and 13 being latched in closed position by means of a hook 14. The hinge element 13 is provided with a pair of elevated horizontal portions 13a and a central lower horizontal portion 14a, the hinge element 12 being wound about the horizontal portions 13a to form the hinge connection. The central horizontal portion 14a is provided with a sleeve roller 16 for cooperation with the latching portion 14b of hook 14. The hook 14 is pivotally carried at its lower end by a support member 17 having its ends embedded in the hanger element 10 in the same manner as the respective ends of the hinge arms 12 and 13 are embedded therein. The respective hinge elements 12 and 13 are urged apart by a torsion spring 18 and said hinge elements and part of the hook constitute a clamping means to hold the hanger elements together with a garment therebetween.

The upper portions of the respective hanger elements 10 and 11 are similar and are formed along the upper surfaces as coat supporting means and have on their abutting inner surfaces

5 respective pairs of pads 21 for engagement with the opposite sides of a garment to be supported therebetween. To provide strength and also to aid in the coat supporting function of the respective hanger elements, a plurality of transverse stiffening ribs 22 and 23 are provided along each hanger element with the upper rib 22 forming a smooth downwardly curved extension of the top coat supporting surface.

10 The hanger element 11 is provided with depending end portions 26 which terminate in inwardly curved hooks 27 for garment supporting purposes and these depending end portions 26 are connected by an integral garment supporting bar 28.

15 While I have shown and described a preferred embodiment of the invention it will be understood that the invention is capable of variation and modification from the form shown so that its scope should be limited only by the scope of the claim appended hereto.

20 I claim:

25 A hanger comprising a pair of opposed hanger elements for holding a garment therebetween, said elements having their upper surfaces at substantially the same elevation, each of said elements along said surfaces including a rib to stiffen same and increase the transverse dimension of the hanger to better support a coat, said 30 ribs extending outwardly in opposite directions from the meeting plane of said elements, and clamping means coacting with and carrying said elements.

35 GRACE M. CLOVER.
